TIME CONTROLLED MECHANISM

John A. L. Deters, Chicago, Ill.

Application April 9, 1941, Serial No. 387,567

1 Claim. (Cl. 200—35)

The present invention relates to a time controlled mechanism, and is more particularly directed to means attachable to a clock whereby the mechanism will be operated in timed relation with predetermined settings of the clock.

Heretofore, various kinds of time controlled mechanisms have been proposed, and in order to accomplish the desired results, special clocks were designed to contain certain mechanism, either mechanical or electrical, and each design varied in accordance with the mechanism to be controlled.

It is an object of the present invention to employ a standard type of clock and to attach mechanism thereto to be controlled thereby with the least amount of altering, and which mechanism will not hamper or retard the normal operation of the clock.

Another object is the provision of mechanism attachable to and controlled by the alarm system of a clock whereby the mechanism may be operated at a predetermined time.

A further object is the provision of mechanism attachable to the alarm system of a clock and operated upon each cycle of its turning movements as the alarm system is released for operation in accordance with a predetermined set time; the number of operations being determined by the number of turns given the alarm system while winding the same preparatory to the setting thereof.

Other objects and advantages of the invention will become apparent from the following description and the accompanying drawings in which:

Figure 1 is a front view of a clock embodying my invention.

Figure 2 is a rear view of Fig. 1, illustrating the operative mechanism.

Figure 3 is a partial detail rear view of a clock, illustrating a bracket attached thereto supporting a combination switch and socket in spaced relation with the clock and with a pull chain depending therefrom and attached to a crank means of the alarm system.

Figure 4 is a side elevation of Fig. 3 with the alarm winding crank removed to show the alarm shaft.

Figure 5 is a partial detail rear elevation of a clock illustrating an eccentric attached to the alarm system thereof.

Figure 6 is an enlarged sectional view taken on the line 6—6 of Fig. 2, showing a crank means attached to the alarm system.

Figure 7 is an enlarged detail perspective view of the chain clip removably attached to the crank means.

Figure 8 is an enlarged cross-sectional view taken on line 8—8 of Fig. 5.

Figure 9 is an enlarged detail sectional view of the manually adjusted alarm control mechanism, taken on line 9—9 of Fig. 2.

Figure 10 is a sectional view taken on line 10—10 of Fig. 9.

Figure 11 is an enlarged detail perspective view of a crank means attachable to the alarm system and formed to provide yieldable means to prevent over-winding.

Figure 12 is an enlarged detail plan view of a crank means attachable to the alarm system and constructed to free itself from a pull chain after a single turning operation thereof.

Figure 13 is an enlarged perspective view of a chain fastening ring for forming a loop at the free end of the pull chain.

Figure 14 is an enlarged detail sectional view of an adjustable means whereby the loop may be adjusted with respect to the pull chain.

Referring more particularly to Figs. 1 to 4, the clock 15 is of the conventional manually wound type, and is shown as having a crank arm 16 attached to the alarm shaft 16a by a hub 17 adjustably secured to the crank arm by a screw 18 (Fig. 6). The crank arm 16 is preferably of channel formation, and is provided with an elongated slot 19 through which the screw 18 passes and is threaded into the hub 17 to adjustably position the crank arm 16 for the desired throw thereon, and the opposite end of the hub 17 is provided with a thread 20 to receive the threaded end of the alarm shaft 16a.

At one end of crank arm 16 is secured a crank pin 21, which is adapted to receive a clip 22 secured to one end of a pull chain 23 which has its other end operatively attached to a combination switch and socket 24 supported on the clock 15 above the alarm control mechanism A.

The combination switch and socket 24 is preferably supported on a stud 25 attachable to the clock casing (Figs. 1, 2, 9 and 10), and which stud has a reduced threaded end 26 that depends through an opening 27 of the casing of the clock 15 and is secured thereto by a washer and nut 28 and 29, respectively. The upper end of the stud 25 is provided with a reduced portion 30 which has an annular groove 31 therein, and which reduced portion 30 receives the shank 24a of the combination switch and socket 24 and with the

screw 32 of the shank 24a threaded into the groove 31 for securing the same to the stud 25.

Provision is also made whereby the alarm system also operates while the combination switch and socket 24 is being operated. In order to accomplish this feature, the stud 25 is provided with a longitudinal bore 33 which slidably receives an alarm lock pin 34 therein, and which pin is provided with a slot 35 at its upper end portion and with a small transversely extending bore 36 near the lower end of the slot 35. The bore 36 is aligned with a transverse elongated slot 37 provided in the stud 25 and receives a small pin 38 therethrough which extends outwardly on each side of pin 34 and through the elongated slot 37 of stud 25. This pin 38 also extends a few thousandths of an inch outwardly on each side of the stud 25 to be frictionally secured to a sleeve 39 which is adapted to slidably fit over the stud 25, and when moved, to carry the pins 38 and 34 for vertical movements therewith to effect the engagement and disengagement of pin 34 with an arm 40 of a bell hammer 41. This movement of pin 34 will lock or release the bell hammer for movement in accordance with the timed setting of the clock.

The arm 40 and bell hammer 41 are of the usual type employed in an alarm clock and are bodily carried for rocking movements on a pivot 42, and have a relatively short extension 43 engageable by a wheel 44 for effecting their movement when released to cause the bell hammer 41 to strike a bell 45.

As thus far described, it will be noted that in order to wind the alarm, the clip 22 is removed from the pin 21 of the crank arm 16 attached to the alarm shaft 16a, and this crank arm 16 is manually gripped and turned the number of revolutions desired, that is, in the type of combination switch and socket 24 shown, a full winding cycle of the crank arm 16 will effect a downward movement of the pull chain 23 to control the switch for "on" position during its unwinding movement, whereas two winding turns of the crank arm 16 will effect two downward movements of the pull chain 23 which is "on" and "off" position during the unwinding movement of the crank arm 16. Likewise, an odd number of winding turns effect a plurality of "on" and "off" positions during the unwinding turns, which ends with the "on" position, and an even number of winding turns effects a number of "on" and "off" positions during unwinding which ends with the "off" position of the switch 24.

As above pointed out, the number of turns given the alarm shaft 16a while winding the alarm system, predetermines the position at which the switch 24 will remain when the alarm is exhausted, the alarm being set in the usual manner by positioning the alarm hand 46 to the desired time by the turning movements of the alarm knob 47 at the back of the clock (Fig. 2). The sleeve 39 attached to the pin 34 (Figs. 9 and 10) effects the release of the arm 40 to permit the hammer 41 to strike the bell 45 simultaneously with the operation of the switch 24 and spring 39a frictionally resists movement of pin 34.

The combination switch and socket 24 is illustrated as having an electric lamp 48 attached thereto and which lamp is lighted in accordance with the "on" and "off" movements of the switch, the current being supplied to the lamp through the leads 49 and 50 which are attached to a source of electric supply. The switch 24 is preferably of a type having two outlet connections

51-52 on each side thereof to either of which may be attached electrical devices to be controlled by my mechanism.

While I have illustrated in Figs. 1 and 2, the combination switch and socket 24 as being carried on a stud 25, it may be carried by a bracket 53 (Figs. 3 and 4) secured to a bolt 54 of the clock 15, and which bracket has a stud 55 to which the switch 24 is secured. With this type of bracket 53, the usual alarm control button 56 of the clock remains intact, and the bracket is of sufficient length to render the alarm button 56 accessible for positioning the same to "on" or "off" position.

Referring more particularly to Figs. 5 and 8, an eccentric 57 is illustrated to perform the functions of the bell crank 16, and is arranged as a pulley, being provided with an annular groove 58 to receive the pull chain 23a therearound and which pull chain is turned back on itself and secured to form a loop 59 by means of a chain fastening ring 60 (Fig. 13). The eccentric 57 is also provided with a finger piece 61 for manually winding the alarm system and which is accomplished without the removal of the pull chain 23a from the eccentric 57, as the loop 59 of the chain permits the same to slip within the groove 58 of the eccentric.

The chain fastening ring 60 (Fig. 13) is preferably of tubular formation with one edge provided with three equidistant slots 60a that each terminate into a cross-slot 60b centrally of the width of the ring 60. The loop 59 in the pull chain is formed by positioning the chain through two of the slots 60a and with the free end of the chain positioned through the remaining slot 60a. As a tension is exerted on the chain 23a, it will be caused to enter into the cross-slots 60b on one side or the other of the slots 60a which securely retains the chain 23a to the fastening ring 60.

The clip 22 illustrated in Fig. 7, is of U-formation and is provided at each of its extremities with an annular opening 62 and with a ball-receiving opening 63 near the bent over portion thereof, and with a slot 64 extending from each of the openings 62 through the opening 63.

A modified form of key 65 is illustrated in Fig. 11, and is provided with a hub 66 to be attached to the alarm shaft 16a of the clock, the other end of the hub 66 is slotted at 67 to receive one end of a coiled key body 68 which has a forwardly and transversely extending finger piece 69 and a relatively small shank 70 providing a crank center for the clip when the clip 22 is attached thereto. The clip 22 is attached to the pull chain 23 by passing a ball of the chain through the opening 63, and which ball is then securely held in the U-shaped portion of the clip with the reduced portion of the chain extending through the slot 64 of the clip.

In Fig. 12 is illustrated a modified form of alarm winding key 71 which is constructed in a manner whereby the full chain is attached thereto and is released from the key during a cycle of the unwinding movement of the alarm shaft. The key 71 is provided with a threaded hub 72 and a crossbar 73 for winding the alarm, and this crossbar is provided with a crescent-shaped portion 74 at one end thereof providing an annular opening 75 and a relatively small inwardly directed slot opening 76 communicating therewith. The chain 23 slidingly fits through slot opening 76 of the key and is retained in opening 75 for a partial cycle as the key is turned during the unwinding movements of the alarm shaft 16a. During this movement, the key automatically discon-

ncts itself from the chain 23 after the chain has been pulled the proper distance for effecting the "on" position of the switch 24. The disconnecting of the chain from the key 71 is accomplished by the turning movement of the key when the reduced portion of the chain will pass through opening 76 after the chain has been pulled a certain distance.

In Fig. 14 is illustrated a modified form of pull chain securing and adjusting means 71 which comprises an internally threaded tubular member 78 which has a cross-member 79 secured at one end thereof and with a slot 80 at each end of the cross-member to which the free ends 81 of a looped chain 82 are secured. The pull chain 23b is secured to the adjusting means 71 by a split tubular collar 83 provided with a thread 84 and threaded into tubular member 78. The pull chain 23b is positioned in the tubular member 78 which has inwardly directed lugs 85 which grip the chain when the split collar 83 is threaded in the tubular member 78. To adjust the pull chain with respect to the loop, it is only necessary to turn the collar 83 in one direction or the other.

While I have illustrated means for securing and adjusting the pull chain in order to properly position the same for effecting the operation of

the combined switch and socket, a further adjustment may be had by pivotally adjusting the combination switch on either of the studs 30 or 55 by merely loosening the set screw 32 thereof and turning the same to the proper position.

It will be apparent from the foregoing that the invention provides a novel means for effecting the control of a combination switch and socket, and the parts are always held in their proper relationship and are easily attached to the conventional type of clock without materially altering the same.

I claim:

In a time controlled device for a clock having an alarm mechanism including an alarm winding shaft, the combination with an electrical switch supported on said clock, of a switch operating transmission between said shaft and said switch, said transmission including an eccentric on said shaft, a pull member looped to form a strap around said eccentric to operate said switch with each rotation of said shaft, and means to adjust the throw of said eccentric on said shaft in accordance with the operating requirements of said switch.

JOHN A. L. DETERS.
